UNITED STATES PATENT OFFICE.

ISAAC P. TURNER, OF TROY, NEW YORK, ASSIGNOR OF ONE-HALF TO JOHN H. COLBY, OF SAME PLACE.

SASH-FASTENER.

SPECIFICATION forming part of Letters Patent No. 247,440, dated September 20, 1881.

Application filed August 12, 1881. (No model.)

To all whom it may concern:

Be it known that I, ISAAC P. TURNER, a citizen of the United States, residing at Troy, in the county of Rensselaer and State of New York, have invented new and useful Improvements in Combined Sash Lift and Fastener, of which the following is a specification.

My invention relates to devices employed for supporting and locking a car or other window-sash, the object being to utilize for operating the sliding locking-bolt a device which is usually rigidly attached to the frame of the sash in position to be grasped so as to facilitate the raising or lowering of the same. This object I attain by the devices hereinafter described, and illustrated in the annexed drawings, in which—

Figure 1 is a side elevation of a window-sash with my improvement applied thereto. Fig. 2 represents the operative devices with the vibratory lift detached. Fig. 3 is a side view of the vibratory lift removed. Fig. 4 represents the rivet or screw-pin for the vibratory sash-lift.

The letter A indicates an ordinary car-window sash, and B a portion of one of the sides of the window-frame, provided with suitable stops or catches, C, for engaging the spring sash-bolt, in order to lock the sash in any required position. The sash-bolt D, which engages the said stops, is made of such length as to adapt it to be operated by means of a device which is located at or about midway of the ends of the lower portion of the sash-frame, and which, while serving as a medium for retracting the bolt, also subserves the purpose of the usual sash-lift.

The sash-bolt, which is preferably formed of a flat metal bar, is provided at its inner end with a flat head, E, formed with a central opening, e, of sufficient area to receive the hub of a bed-plate that is secured to the sash-frame, and also to receive the spring F, arranged to press against the said hub and against one of the walls of the said opening in the bolt-head, so as to normally throw the bolt forward. The bed-plate G, upon which this flat recessed head of the bolt slides, is secured to the middle of the lower part of the sash-frame, and can, if

desired, be seated in a mortise formed in the wood-work, or it can be secured to the frame without mortising the same.

H indicates the double-armed vibratory sash-lift employed for raising or lowering the sash, and also for drawing back the bolt, in order to clear its outer end of the stops during the vertical movement of the sash. This vibratory sash-lift comprises a flat metal plate or body, h, having at opposite edges the two outwardly-projecting curved arms, h' h'', the said arms being bent or curved at their ends inwardly and toward each other, the curvature of these arms being such that the concavity formed adapts each to receive a finger or fingers of the person desiring to grasp the sash-lift for the purpose of raising or lowering the sash. The flat plate or body of the lift covers the spring and the recessed head of the bolt, and is retained thereon by means of a screw-threaded pin, I, which passes through a central perforation of the said double-armed lift, and is screwed into the hub i of the bed-plate. The double-armed lift turns freely upon this screw pin or pivot when the device is constructed as herein shown, although in practice I may cast the pin in one piece with the lift-plate and swivel the pin in the hub or the bed-plate, which will be suitably constructed for such purpose.

The lift-plate is provided upon its inner face with a stud, K, which is arranged to extend into a notch, L, formed in one edge of the flat head that is at the inner end of the sash-bolt, the width of such notch being sufficient to allow a certain extent of play on the part of the stud.

Now, by turning the vibratory lift-plate to the left, its stud, striking against one of the walls of the notch, will force the bolt back against the spring-pressure, and hence retract its locking end from the line of stops, so as to unlock the sash.

The notch of the bolt-head and the stud of the vibratory lift-plate have such relative arrangement that when the parts are fitted together and the bolt thrown forward by its spring the lift-plate will normally stand at an angle of about forty-five degrees—that is to say, a line taken longitudinally through the

lift-plate and both of its arms will be at such an angle with respect to a vertical line taken through the pivotal center of the lift. The necessity and the advantages of this arrangement 5 will appear from the following:

The sash being closed and the bolt thrown forward, the lift-plate will be at an angle with its upper arm to the right of a vertical line taken through its pivotal center. Now, when 10 a person desires to raise the window the first and the most natural movement will be to grasp the upper arm of the vibratory lift and pull upwardly upon the same. This effort will obviously turn the lift-plate upon its pivot, so as 15 to retract the bolt. After the plate has been thus turned, so as to bring the same into a vertical line, a continuance of the upward pull or tension thereon will raise the sash to the required height. Now, the sash being raised and 20 the vibratory lift liberated, the spring will throw the bolt forward to engage one of the stops, and consequently the notched head of the bolt will turn back the vibratory lift, so that it will stand at an angle, as before. Now, 25 when it is desired to unlock and lower the sash the most obvious and natural way will be to grasp the lower arm of the vibratory lift and pull down upon the same. This action on the part of the operator will effect the same movement of the bolt as before, since the vibratory lift will turn until it assumes a vertical position and the bolt has been retracted from the stop with which it has engaged, after which, 30 the sash being free, it can be readily lowered by drawing upon the said lower arm of the vibratory lift. The bolt will pass through a suitable strap or casing, L', arranged near the edge of the sash-frame, by means of which the bolt will be guided and steadied in its action. 35 40 The form of stop employed may be consider-

ably varied, that herein shown consisting of a casting, C, provided with holes for the fastening-screws, and having a horizontal seat, m, to check the bolt, and an inclined face, m', for the bolt to strike against and ride over after it has 45 been released from its locked condition.

As a means for further steadyng the vibratory lift-plate I may provide it with a second stud, O, adapted to work in a long notch or recess in the bolt-head, said stud bearing against 50 the bed-plate, as will also the stud hereinbefore referred to.

Heretofore a sash lift and fastener has been composed of a bolt connected with an operating-handle at the center of the sash, and extending to the edge of the latter, for engaging and disengaging stops on the window-jamb, and therefore I do not broadly claim such features. 55

Having thus described my invention, what 60 I claim is—

The combination, with a sash-frame, of the sliding locking-bolt having a flat inner end or head formed with a central opening, and with a notch in one edge thereof, the spring arranged 65 within said opening for the purpose of throwing the bolt forward, and the double-armed vibratory lift pivoted over said head of the bolt, and provided with a stud entering the said notch, the pivotal point of the vibratory lift 70 being at the center of the lower portion of the sash-frame, substantially as described.

In testimony whereof I have hereunto set my hand in the presence of two subscribing witnesses.

ISAAC P. TURNER.
